SLIDE FASTENER DEVICE

Harvey L. Williams, Greenwich, Conn., and Paul S. Kellum, Newark, N. J., assignors to Crown Fastener Corporation, Warren, R. I., a corporation of Delaware

Application October 31, 1942, Serial No. 463,996

10 Claims. (Cl. 24—205)

This invention relates to fastening structure of the type in which two series of cooperating fastening elements mounted on tapes are coupled and uncoupled by the movement of slide structure longitudinally of said series.

One of the objects of the invention is to provide structure which will enable the operator to maintain between said series of fastening elements an opening of predetermined dimensions which may be moved progressively along said tapes longitudinally thereof by maintaining the fastening elements corresponding to said opening in uncoupled condition while maintaining the remainder of the fastening elements of said tapes in coupled condition.

The principles of the invention will be defined in the claims.

One embodiment of these principles will be described by reference to the accompanying drawing illustrating a machine gun turret slot closure, in which

Fig. 1 is a view on line 1—1 of Fig. 2 showing a gun barrel protruding through an opening between a pair of tapes provided with separable fasteners;

Fig. 2 is an edge view looking in the direction of the arrow in Fig. 1;

Fig. 3 is a section on line 3—3 of Fig. 1; and

Fig. 4 is a section on line 4—4 of Fig. 1.

It will be understood of course that numerous other embodiments of the principles of the invention and departures from the specific form shown herein may be made while still embodying the principles disclosed and claimed.

In accordance with the invention, slide structure is provided including a body portion. This may take the form of a ring 1 having an opening defined by peripheral inner surface 2. A gun barrel 3 protrudes through this opening. The body portion or ring 1 has curved parts, partly defined by outer surfaces 4, which are disposed about and in spaced relation to the inner peripheral opening-defining surface 2. The said curved parts 4 are adapted to form fastener-riding paths, as will more fully hereinafter be explained.

From each of the sides of the transverse line 4—4 of Fig. 1, each pair of riding paths 4A—4B and 4C—4D converge toward each other and join or merge into single fastener-guiding channels in sliders 5 and 5A, respectively, at each of two oppositely disposed parts of the slide structure. These single fastener-guiding channels in sliders 5 and 5A may take the form of conventional slide structure having channels 6 separated by web 7.

The channels 6A, 6B are aligned with fastener-riding paths 4A and 4B, respectively, and the channels 6C, 6D are aligned with fastener-guiding paths 4C, 4D, respectively.

5 The sliders 5, 5A include top and bottom walls 8 from which flanges 9 depend in spaced relation, as shown, forming slots 10 to permit the passage of tapes 11.

The sliders 5, 5A may be pivotally joined to the 10 ring 1 by means of pins 13 mounted in brackets 14 welded or otherwise secured to the ring 1, the pins 13 passing through holes in the webs 7.

One of the applications of the invention is the provision of a closure for the elongated slot in 15 a machine gun turret, the gun being mounted so that the barrel thereof may be swung through a desired part of the slot. By using this invention, the turret slot may be maintained in closed condition, notwithstanding movement of the gun 20 barrel, at substantially all points except the opening in the slide structure through which the gun barrel protrudes. Of course the gun barrel must move back and forth in its slot. Therefore the fastening elements 12 must be adapted 25 and constructed so that they will readily close or open when the slide structure is moved in either direction longitudinally of the tapes by the gun barrel.

The specific form of fastening element shown 30 may be used to perform the stated function in cooperation with the slide structure by spacing the elements 12, as shown, to such an extent that they will not jam when the slider moves, to engage said elements, in a direction opposite to that 35 normally employed to close that specific form of element. Another form of element which may be used is shown in United States Patent No. 1,571,095, issued January 26, 1926, to Perrault. In general, any form of the complementary elements of the two series thereof mounted on their 40 respective tapes, which is adapted to permit said series of elements to readily engage and disengage by movement of the slide structure in either direction longitudinally of said tapes, may be used.

The specific form of fastener-riding paths (4A to 4D) shown permits the fasteners or scoops 12 to turn through an angle of ninety degrees as they emerge from the channels 6A, 6B, 6D and 50 6C and to follow an arcuate path as shown most clearly in Fig. 2. This tends to prevent distortion of the tape when the slot closure is of limited width.

We claim:

1. Separable fastener slide structure adapted

to couple and uncouple two series of cooperating fastening elements mounted on tapes and to maintain between said series of fastening elements an opening of predetermined dimensions which may be progressively shifted along said tapes longitudinally thereof by maintaining the fastening elements corresponding to said opening in uncoupled condition while maintaining the remainder of the fastening elements of said tapes in coupled condition, said slide structure comprising a body portion having an opening therein, said opening being defined by peripheral surface of said body portion, said body portion having a pair of spaced fastener-riding unconfined paths defined by curved parts of said body portion, said curved parts being disposed about and in spaced relation to said peripheral opening-defining surface, a pair of slider structures including converging fastener-guiding confined channels partly defined by top and bottom walls and a transverse web member and converging into a single fastener-guiding confined channel, said slider structures disposed at each of two opposite parts of said slide structure and pivotally joined to said body portion, said fastener-riding unconfined paths converging toward each other adjacent each of said opposite parts and said convergent riding paths being aligned with said converging guiding confined channels, respectively.

2. Separable fastener slide structure adapted to couple and uncouple two series of cooperating fastening elements mounted on tapes and to maintain between said series of fastening elements an opening of predetermined dimensions which may be progressively shifted along said tapes longitudinally thereof by maintaining the fastening elements corresponding to said opening in uncoupled condition while maintaining the remainder of the fastening elements of said tapes in coupled condition, said slide structure comprising a body portion having an opening therein, said opening being defined by peripheral surface of said body portion, said body portion having a pair of spaced fastener-riding unconfined paths defined by curved parts of said body portion, said curved parts being disposed about and in spaced relation to said peripheral opening-defining surface, said riding paths converging toward each other and merging into a single confined channel within sliders attached to said body portion at each of two opposite parts of said slide structure respectively, each slider being pivoted to said body portion.

3. A slide structure including a pair of tapes, two series of complementary and cooperating separable fastening elements mounted on said tapes and means adapted to maintain between said series of fastening elements an opening of predetermined dimensions which may be shifted progressively along said tapes longitudinally thereof by maintaining the fastening elements corresponding to said opening in uncoupled condition while maintaining the remainder of the fastening elements of said tapes in coupled condition, said structure including a slide comprising a body portion having an opening therein, said opening being defined by peripheral surface of said body portion, said body portion having a pair of spaced fastener-riding unconfined paths defined by curved parts of said body portion, said curved parts being disposed about and in spaced relation to said peripheral opening-defining surface, a pair of converging fastener-guiding confined channels formed within slider structures pivoted to said body portion, said slider structures partly

defined by top and bottom walls and a transverse web member and converging into a single fastener-guiding confined channel, at each of two opposite parts of said slide structure said fastener-riding unconfined paths converging toward each other adjacent each of said opposite parts, said convergent riding paths being aligned with said converging guiding channels, respectively, and said structure further including complementary and cooperating fastening elements adapted to be readily coupled and uncoupled by movement of said slide structure in any direction longitudinally of said tapes.

4. Separable fastener slide structure adapted to couple and uncouple two series of cooperating fastening elements mounted on stringers and to maintain between said series of fastening elements an opening of predetermined dimensions extending progressively along said stringers longitudinally thereof by maintaining the fastening elements corresponding to said opening in uncoupled condition while maintaining the remainder of the fastening elements of said stringers in coupled condition, said slide structure comprising two sliders each having a narrow end and a wide end and a pair of walls connected to and spaced by a web portion and partly defining a pair of channels converging at the narrow end and diverging at the wide end; means connecting said sliders and adapted to maintain them in spaced relation longitudinally of said stringers and with the wide ends of the sliders facing each other, said sliders and means being pivotally connected; and arcuate guiding means between said sliders spaced laterally of said stringers providing movement of said fastening elements relatively to said means in arcuate unconfined paths concave in relation to each other and aligned with the divergent channels of the sliders.

5. Separable fastener slide structure adapted to couple and uncouple two series of cooperating fastening elements mounted on stringers and to maintain between said series of fastening elements an opening of predetermined dimensions extending progressively along said stringers longitudinally thereof by maintaining the fastening elements corresponding to said opening in uncoupled condition while maintaining the remainder of the fastening elements of said stringers in coupled condition, said slide structure comprising two sliders each having a narrow end and a wide end and a pair of walls connected to and spaced by a web portion and partly defining a pair of channels converging at the narrow end and diverging at the wide end; guiding means, including a ring, connecting said sliders and adapted to maintain them in spaced relation longitudinally of said stringers with the wide ends of the sliders facing each other, portions of said ring being spaced laterally of said stringers and providing movement of said fastening elements relatively to said ring in arcuate unconfined paths concave in relation to each other and aligned with the divergent channels of the sliders, and pivotal connections between said guiding means and said sliders.

6. Separable fastener slide structure adapted to couple and uncouple two series of cooperating fastening elements mounted on stringers and to maintain between said series of fastening elements an opening of predetermined dimensions extending progressively along said stringers longitudinally thereof by maintaining the fastening elements corresponding to said opening in uncoupled condition while maintaining the remain-

der of the fastening elements of said stringers in coupled condition, said slide structure comprising two sliders each having a narrow end and a wide end and a pair of walls connected to and spaced by a web portion and partly defining a pair of channels converging at the narrow end and diverging at the wide end; means adapted to maintain said sliders in spaced relation longitudinally of said stringers with the wide ends of the sliders facing each other, pivotal connections between said sliders and said means; and said means including arcuate guiding means between said sliders spaced laterally of said stringers and providing movement of said fastening elements relatively to said means in arcuate unconfined paths concave in relation to each other and aligned with the divergent channels of the sliders.

7. Separable fastener slide structure adapted to couple and uncouple two series of cooperating fastening elements mounted on stringers and to maintain between said series of fastening elements an opening of predetermined dimensions extending progressively along said stringers longitudinally thereof by maintaining the fastening elements corresponding to said opening in uncoupled condition while maintaining the remainder of the fastening elements of said stringers in coupled condition, said slide structure comprising two sliders each having a narrow end and a wide end and a pair of walls connected to and spaced by a web portion and partly defining a pair of channels converging at the narrow end and diverging at the wide end; guiding means, including a ring, connecting said sliders and adapted to maintain them in spaced relation longitudinally of said stringers with the wide ends of the sliders facing each other, the sliders being pivotally connected to said means, portions of said ring being spaced laterally of said stringers and providing movement of said fastening elements relatively to said ring in arcuate unconfined paths concave in relation to each other and aligned with the divergent channels of the sliders.

8. Separable fastener slide structure adapted to couple and uncouple two series of cooperating fastening elements mounted on stringers and to maintain between said series of fastening elements an opening of predetermined dimensions extending progressively along said stringers longitudinally thereof by maintaining the fastening elements corresponding to said opening in uncoupled condition while maintaining the remainder of the fastening elements of said stringers in coupled condition, said slide structure com-

prising two sliders each having a narrow end and a wide end with curved walls connected to and spaced by a web portion and partly defining a pair of channels converging at the narrow end and diverging at the wide end, means connecting said sliders and adapted to maintain them in spaced relation longitudinally of said stringers and with the wide ends of the sliders facing each other, said means located in the same plane as the plane of said sliders, and arcuate guiding means between said sliders spaced laterally of said stringers providing movement of said fastening elements relative to said means in arcuate unconfined paths concave in relation to each other and aligned with the divergent channels of said sliders.

9. In a fastening device, a pair of fastener stringers each having a continuous series of cooperating fastener elements arranged in uniformly spaced relation along said stringers, a pair of slider structures spaced apart and mounted on said elements and a member connected to each of said slider structures and arranged to hold them in spaced relation to each other on said elements, each of said slider structures having fastener element channels therein which diverge from each other at the end of the slider structure adjacent said member, the fastener elements being disconnected between the ends of said slider structure adjacent said member and fastening means adapted to attach said slider structures to said member, said means adapted to lie in the same plane as the plane of said slider structures and to connect the divergent end of each slider structure to said member.

10. In a fastening device, a pair of fastener stringers each having a continuous series of cooperating fastener elements arranged in uniformly spaced relation along said stringers, a pair of slider structures spaced apart and mounted on said elements, a member connected to each of said slider structures and arranged to hold them in spaced relation on said elements, means comprising a pivot arranged in the same plane as said slider structure for connecting said slider structures to said member at the divergent ends of each slider structure, each of said slider structures having fastener element channels therein which diverge from each other at the end of said slider structure adjacent said member and the fastener elements being disconnected between the ends of said slider structures adjacent said member.
